WIRE CAGE SKELETAL STRUCTURE HAVING TROUGH BEAM AND WIRE PANEL RIBS

Gerald L. Kitson, 9709 Belding Road,
Rockford, Mich. 49341

Filed Feb. 1, 1968, Ser. No. 10,401

Term of patent 14 years

Int. Cl. D30—99

U.S. Cl. D30—41

The drawing figure is a top perspective view of a wire cage skeletal structure having trough beam and wire panel ribs, embodying my new design.

The far end of the skeletal design is the same in appearance as the near end shown.

I claim:

The ornamental design for a wire cage skeletal structure having trough beam and wire panel ribs, as shown and described.
